UNITED STATES PATENT OFFICE.

FRANK HOULE, OF CHICAGO, ILLINOIS.

TRY-SQUARE.

SPECIFICATION forming part of Letters Patent No. 530,894, dated December 11, 1894.

Application filed March 21, 1894. Serial No. 504,533. (No model.)

To all whom it may concern:

Be it known that I, FRANK HOULE, a citizen of the United States, residing in Chicago, county of Cook, and State of Illinois, have invented certain new and useful Improvements 5 in Try-Squares, of which the following is a specification.

My invention relates to try-squares and will be fully described hereinafter.

10 In the drawings Figure 1 is a plan of my device with the blade at right angles to the handle. Fig. 2 is also a plan but with part of the handle broken away to show the connection between the handle and blade. Fig. 15 3 is a plan view of the blade, and Fig. 4 is a section on line 4—4 Fig. 1.

A is the handle which is slotted to receive the blade as the handles of try-squares usually are and B is the blade which differs from 20 other blades in having in one end a slot C. This slot has furcations c c with right angular terminations d and when the blade is in place and extends at right angles from the handle two bolts f and g engage with the terminals and hold the blade firmly in place; 25 but when the blade is to be adjusted to any other angle, the slot permits the blade to be drawn out and given the proper adjustment after which the blade must be secured in 30 place by tightening a thumb nut f' on bolt f.

The blade may be scaled or marked by oblique lines to indicate various angles so that when any angle less than a right angle is desired, the blade is drawn to the left to release the bolts from the terminations of the 35 slots and is then deflected until the proper scale is flush with the face of the handle and then the thumb nut is tightened.

It will be observed that this square naturally locks at right angles and therefore the 40 thumb screw need not be disturbed except to lock the blade at a less angle.

Having thus described my invention, what I claim as new, and desire to secure by Letters Patent, is—

45 The try square consisting of a slotted handle, and a blade in said slot, said blade having a furcated opening, a fixed pin passing through the handle and one branch of the opening in the blade, and a bolt passing 50 through the handle and the other branch of the opening in the blade, said bolt having a tightening nut, substantially as described.

FRANK HOULE.
